PLASTIC FIGURED TEXTILE FABRIC

Robert A. Poisson, New York, N.Y., assignor to Riegel
Textile Corporation, a corporation of Delaware

Filed July 28, 1958, Ser. No. 51,956

Term of patent 14 years

(Cl. D87—3)

Fig. 2

Fig. 1 is a plan view of a plastic figured textile fabric incorporating my new design, the repeating pattern of the design being indicated by solid lines; and

Fig. 2 is an enlarged sectional detail taken substantially on the line 2—2 in Fig. 1.

I claim:

The ornamental design for a plastic figured textile fabric, as shown and described.
